INTERNAL-COMBUSTION ENGINE
CARBURETOR

Andrew Craig Russell, Shawnee, Okla.

Application November 24, 1947, Serial No. 787,760

1 Claim. (Cl. 261—64)

1
This invention relates to internal combustion engine carburetors in the nature of that disclosed in my U. S. Letters Patent No. 2,366,056, dated December 26, 1944, and is a continuation in part of my co-pending application, Serial No. 646,767, filed February 11, 1946, now abandoned.

The most important object of this invention is to provide a carburetor operable on the broad principles set forth in the aforesaid patent and co-pending application, yet capable of more efficient operation, and having refinements of construction lending to simple maintenance and cheapness of manufacture.

Another object of this invention is to improve upon the carburetors forming the subject matter of my co-pending applications bearing the following serial numbers: 691,944, issued as Patent No. 2,506,812 on May 9, 1950; 700,202, now abandoned; 710,519, now abandoned; 747,409, now Patent No. 2,529,665 issued on Nov. 14, 1950; and 765,978, now abandoned filed August 21, 1946; September 30, 1946; November 18, 1946; May 12, 1947; and August 4, 1947 respectively.

Another important object of this invention is the provision of a carburetor having a mixing head interconnecting a fuel bowl and an air inlet chamber, which head is formed integrally with a partition separating said bowl and chamber.

Another object of the present invention is to provide a carburetor having a specially formed, spring loaded, reciprocable valve for controlling the flow of air from an air chamber to a receiving compartment for fuel mixture, operable solely on suction created at an outlet opening communicating with said compartment.

Referring to the drawings:

Fig. 1 is a top plan view of an internal combustion engine carburetor made in accordance with my present invention.

Fig. 2 is a side elevational view thereof.

Fig. 3 is a cross sectional view taken on irregular line III—III of Fig. 2.

Fig. 4 is an elevational view showing one side thereof opposite to that shown in Fig. 2.

Fig. 5 is a cross sectional view taken on line V—V of Fig. 1.

Fig. 6 is a cross sectional view taken on line VI—VI of Fig. 1; and

Fig. 7 is a cross sectional view taken on line VII—VII of Fig. 1.

The carburetor about to be described includes a hollow sectionalized casing broadly designated by the numeral 10 and formed to present a fuel bowl 12, an air chamber 14 and a receiving chamber 16.

A central section 18 of the casing 10, has the receiving chamber 16 that is formed therein, closed by a top section in the form of a covering plate 20 through the medium of a number of bolts or the like 22. A portion of the fuel bowl 12 is also formed in this section 18, while the main part of bowl 12 is created by a cup-like section 24 that is secured to section 18 by bolts 26. Gaskets 28 and 30 are interposed between sections 18 and 20 and sections 18 and 24 respectively.

A partition plate 32 interposed between sections 18 and 24 and held in place by bolts 26, divides the fuel bowl 12 from the air chamber 14 that is disposed within the section 18 of casing 10.

A bracket 34, integral with section 18 has openings 36 formed therein to permit mounting of the carburetor on the intake manifold of an internal combustion engine and an outlet opening 38 communicating at its innermost end with the receiving compartment 16, is provided with a flutter valve 40. This valve 40 is mounted on a rotatable shaft 42 having a link 44 secured to its outermost end externally of casing 10. This link 44 may be connected in any suitable manner with the engine's accelerator (not shown). An arm 46 fastened to link 44 by a screw 48 has a spring-loaded adjusting screw 50 threaded therein and projecting therethrough for engagement with a stop pin 52 mounted in section 18.

An air inlet port 54 communicates with chamber 14 and is provided with a choking valve 56 mounted on a rotatable shaft 58 having a control key 60 at its uppermost end.

A float 62 within fuel bowl 26 is swingably mounted through the medium of an arm 64 that underlies a valve 66. This valve 66 is floatingly mounted in a fuel inlet plug 68 having connection through a conduit (not shown) with a source of fuel. Swinging movement of float 62 thus controls the opening and closing of valve 66, float 62 being set to maintain a section 70 of fuel bowl 12 full during operation of the carburetor. A breather plug 72 mounted in section 18 of casing 10 facilitates such operation.

As shown in Fig. 7, the section 70 of fuel bowl 12 is relatively shallow and channel-like in cross section, and has disposed therein the lowermost end of a mixing head 76. This mixing head 76 is integral with the plate 32 and also extends thereabove into the chamber 14.

A bore 78 through head 76 forms a mixing chamber above the level of fuel in bore 78, such fuel entering bore 78 at its lowermost end through a removable, perforated control plug 80. A set screw 82 threaded in section 24 of casing 10 pro-

vides a drain plug for fuel bowl 12 and also permits removal of plug 80 for cleaning or replacement.

A plurality of downwardly converging passages 84 formed in the uppermost portion of the head 76 are disposed to place bore 78 into communication with chamber 14 and direct air from the latter to the level of fuel in bore 78.

A wall 86, forming the bottom of the compartment, constitutes a portion of the top wall of chamber 14 and overlies the mixing head 76. An opening 88 formed in the wall 86 places the chamber 14 into communication with compartment 16.

A cup-shaped valve 90 has a central opening 92 therethrough for receiving the uppermost end of a conduit 94 upon which it is slidably mounted. The conduit 94 is threaded into mixing head 76 in register with the bore 78 and has its upper end disposed within the compartment 16. A coil spring 96 circumscribing the uppermost end of conduit 94 is interposed between the innermost face of the bottom wall of valve 90 and the plate 20 to yieldably hold valve 90 in closed relation to opening 88. The side walls of valve 90 constitute a number of upstanding fingers 98 for holding spring 96 in place.

In operation, suction created in the compartment 16 by the internal combustion engine draws air into the bore 78 through the passages 84. This same suction opens valve 90 to draw air into compartment 16 from chamber 14 by way of opening 88.

When air impinges upon the level of fuel within the bore 78, vaporization takes place and this mixture of air passes upwardly through conduit 94 to further vaporize as it mixes with air passing into compartment 16.

The extent of opening of the valve 90, as compared with a predetermined degree of opening of the throttle valve 40 depends upon the tension of spring 96, and thus, as valve 40 is moved toward the open position, valve 90 will also move toward the fully open position to admit additional fuel mixture to the internal combustion engine.

Having thus described my invention, what is claimed as new and desired to be secured by Letters Patent is:

In a carburetor for internal combustion engines, a casing including a main section having an open bottom air compartment, an open top re-

ceiving compartment, an inlet and an outlet opening communicating with said air compartment and with said receiving compartment respectively, and a perforated, normally horizontal partition between the air compartment and the receiving compartment; a vertically reciprocable valve in the receiving chamber and closing the perforation of the partition when resting on the latter; a removable cover secured to said main section and closing said open top of the receiving compartment thereof; a removable pan-like, fuel bowl section secured to the main casing section beneath the air compartment thereof; a horizontal plate clamped between said main section and said fuel bowl section, closing said open bottom of the air compartment and separating the latter from the fuel bowl; a float chamber formed in said main section and in said fuel bowl section, communicating with the latter and separate from the compartments; a head integral with said plate and extending into the air compartment and into the fuel bowl, said head having a bore therethrough registering with the fuel bowl; and a vertical, tubular guide for said valve supported by said head and across the air compartment through the perforation for placing the fuel bowl into communication with the receiving compartment by means of said bore, there being a number of inclined air passages formed in said head interconnecting the bore with the air compartment, said perforation having a diameter greater than the outside diameter of said tubular guide for placing the air and receiving compartments into registering relationship on upward movement of the valve on the guide away from said partition.

ANDREW CRAIG RUSSELL.
